Patented Mar. 30, 1909.

UNITED STATES PATENT OFFICE.

JOHN H. OWEN, OF STUTTGART, ARKANSAS.

PUMP.

No. 916,583.

Specification of Letters Patent. Patented March 30, 1909.

Application filed September 2, 1908. Serial No. 451,417.

To all whom it may concern:

Be it known that I, JOHN H. OWEN, a citizen of the United States, residing at Stuttgart, in the county of Arkansas and State of Arkansas, have invented certain new and useful Improvements in Pumps, of which the following is a specification.

This invention comprehends certain new and useful improvements in lift pumps of 10 that type which operate on the centrifugal principle, and the object of the invention is an improved machine of this character, the parts of which are so arranged and braced as to render the pump susceptible of being 15 swung into position in a pit, or lake, or the like, without sustaining any injury, and which embodies improved means for effectually raising the water and also reducing the friction of the same within the casing, 20 thereby increasing the efficiency of the pump and effecting a material economy in the power required to operate the same.

With this and other objects in view that will more fully appear as the description proceeds, the invention consists of certain constructions, arrangements and combinations of the parts that I shall hereinafter fully describe and then point out the novel features thereof in the appended claim.

For a full understanding of the invention, reference is to be had to the following description and accompanying drawings, in which:

Figure 1 is a vertical section of a pump 35 constructed in accordance with my invention; Fig. 2 is a top plan view of the wheel with the inner member removed, and Fig. 3 is a transverse section.

Corresponding and like parts are referred 40 to in the following description and indicated in all the views of the drawings by the same reference characters.

Referring to the drawing, the numeral 1 designates a substantially vertically disposed 45 tubular pump casing that is preferably constructed in a plurality of sections 2 formed at their ends with outstanding annular flanges, by means of which the sections are detachably coupled together by bolts or 50 other suitable fastening means. The lowermost section 2 constitutes an intake and is designed to be submerged in the water to be raised, and to conduct the same to an enlargement 4 formed intermediate of the ends 55 of the casing and having its lower portion preferably hollow and semi-spherical in form,

while its upper portion tapers upwardly to the ordinary diameter of the pump casing, as shown. The uppermost section 2 has a lateral tubular projection constituting a discharge pipe or spout 5, and is provided at its upper end with a centrally perforated head 6 which is formed around the perforation with an upwardly disposed hollow boss 7 in which fits the upper end of a longitudinal pipe 8. 60 The extremity of this pipe 8 is enlarged as shown, so as to rest upon the upper edge of the boss and be sustained thereby, said enlarged portion of the pipe being also designed to accommodate a run-way 9 having a 65 plurality of antifriction balls 10 upon which rests a relatively stationary collar 11 secured on a vertical pump shaft 12 so as to suspend the same within the pipe 8 and render it susceptible of rotation therein. 75

Rigidly secured upon the upper extremity of the shaft 12 above the collar 11 is a pulley 13 around which extends a drive belt 14 that is designed to transmit motion to the pulley from an engine or other suitable source of 80 power not shown. In order to increase the frictional contact of the drive belt with the pulley, I preferably provide an idler or belt tightener 15, the spindle 16 of which is journaled in a preferably brass bearing 17 that 85 is secured within a box or casting 18 by means of a set screw or the like, said box being supported upon an outstanding arm 19 carried at the upper end of the pump casing 1. 90

The shaft 12 and the pipe 8 in which it is 95 revolvably mounted, extend downwardly into the pump casing 1 and are preferably constructed in two or more sections that are suitably coupled together, the pipe 8 being preferably sustained centrally within the 95 pump casing by means of a spider 20. The lowermost section of the pipe 8 terminates in the upper portion of the enlargement 4 of the casing and fits within a longitudinally disposed sleeve 21 that is supported therein 100 by means of a plurality of braces 22, the pipe being formed at its extremity with an outstanding flange 23 adapted to abut against the adjacent end of the sleeve and the pipe is provided in proximity to the other end of 105 the same with a coupling collar 24 whereby to hold the pipe against any longitudinal movement in either direction through the sleeve. The shaft 12 projects downwardly beyond the pipe 8 into the lower portion of 110 the enlargement 4 and carries a water wheel which is designed for revolution therein to

effect the elevation of the water in the casing and which in the present instance is constructed in inner and outer downwardly tapering members 25 and 26, the same being preferably in the form of concentric hemispheres and the outer member being hollow and incasing the inner member in spaced relation thereto, as shown. The inner member 25 is keyed or otherwise secured upon 5 the shaft in any approved manner, so as to rotate therewith, and the outer member 26 is supported from the inner member through the instrumentality of a plurality of blades 27 which are interposed between the members 10 and preferably have a spiral arrangement as best seen in Figs. 1 and 2, and which divide the space between the sections into a plurality of winding water ways that lead from a central aperture 28 extending through 15 the outer member 26 in registry with the intake 3, to the upper end of the water wheel. 20

From the foregoing description in connection with the accompanying drawing, it will be apparent that as motion is transmitted to the pulley 13 by means of the drive belt 14, the rotation of the shaft 12 and the water wheel attached thereto, will be effected. As the water wheel turns, the air in the winding water ways is thrown outwardly and upwardly by centrifugal force 25 and a vacuum is thus created in the space between the members 25 and 26, whereby to cause a suction through the intake 3 and draw the water upwardly through the same 30 into the enlargement 4 of the casing. The water as it thus flows into the winding water ways of the wheel, is discharged therefrom by means of the centrifugal action and is forced upwardly through the pump casing 1 35 and discharged through the pipe or spout 5, the water continuing to be raised as the pump remains in operation. It is to be particularly observed, however, that as the water leaves the water ways at the upper end 40 of the wheel, the outward and upward twist that it receives therefrom, causes it to flow along the tapering upper portion of the enlargement 4 and to follow the same and be directed thereby into the main portion of 45 the casing, whereby the frictional contact of the water with the sleeve and the lower portion of the pipe 8 is considerably reduced to effect a material economy in the power required to raise the water in the pump and 50 also increase the output of the same. In 55

the present instance, in order to further reduce the friction within the pump, I preferably provide an oil cup 29 which is supported in any suitable manner from the pump head 6 above the antifriction bearing 10 and which is designed to conduct the oil to said bearing by means of a feed pipe 30 which extends downwardly below the lower end of the pulley and then upwardly between the same and the hollow boss 7, the oil overflowing from the antifriction bearing and passing down between the shaft 12 and the pipe 8 in which the same is journaled, so as to effect the lubrication of said journal and thus substantially all of the movable parts 70 of the machine. Attention is directed to the fact that the lower end of the belt idler 15 is formed with an outstanding annular flange serving to keep the belt and pulley from dropping down. 75

Having thus described the invention, what is claimed as new is:

A centrifugal pump of the character described, comprising a hollow casing provided at its opposite ends with an intake and a discharge outlet and formed intermediate of its ends with a lateral enlargement, the upper and lower portions of the enlargement tapering oppositely, a longitudinal shaft journaled within the casing and extending into the enlargement, and a transversely disposed water wheel rigidly mounted upon the shaft and arranged entirely within the lower portion of the enlargement and designed for rotation therein, said water wheel consisting of inner and outer members tapering similarly to the lower portion of the enlargement, the outer member substantially incasing the inner member in spaced relation thereto and being formed with a central aperture in registry with the intake, and a plurality of spirally arranged blades interposed between the members and rigidly secured thereto and dividing the space between the same into a plurality of winding waterways leading from the central aperture and adapted to discharge water against the upper tapered portion of the enlargement. 90

In testimony whereof I affix my signature in presence of two witnesses.

JOHN H. OWEN. [L. S.]
